US00D947872S

(12) **United States Design Patent** (10) **Patent No.:** **US D947,872 S**
(45) **Date of Patent:** **** Apr. 5, 2022**

(54) **MICROSCOPE DISPLAY SCREEN WITH GRAPHICAL USER INTERFACE**

(71) Applicant: **Leica Microsystems CMS GmbH**, Wetzlar (DE)

(72) Inventor: **Stefan Huber**, Schoenau (DE)

(73) Assignee: **Leica Microsystems CMS GmbH**, Wetzlar (DE)

(**) Term: **15 Years**

(21) Appl. No.: **29/782,419**

(22) Filed: **May 6, 2021**

CLAIM

The ornamental design for a microscope display screen with graphical user interface, as shown and described.

DESCRIPTION

The FIGURE shows a graphical user interface element on a display screen of a microscope system at the edge of the display screen.

The broken lines in the accompanying drawing illustrates environmental structure that forms no part of the claimed design.
